CLAVICLE SPLINT

Application filed September 19, 1931. Serial No. 563,846.

The invention relates to surgical splints designed primarily for use in the reduction of fractures of the clavicle.

Heretofore clavicle splints of various types have been used which are applied upon the back of the patient with pad-carrying straps passed over the shoulders and under the arms. The straps when drawn tight are irritating to the axillæ and the effective bearing surface of the pads is substantially limited to the width of the straps. Since the purpose of the splint is to draw the injured shoulder back into proper position to secure alignment of the separated or fractured segments of the clavicle, it is an advantage to have a large surface in engagement with the forward side of the shoulder so that the pressure exerted thereon shall be uniformly distributed over said shoulder and secure the proper rearward movement thereof. It is also a distinct advantage if this bearing surface shall conform to the contour of the forward side of the shoulder, and also that the shoulder engaging parts shall push the shoulders rearwardly rather than pull them rearwardly as in prior devices.

The object of my invention is to provide a novel splint having the advantages set forth above, and another object is to provide a splint having a large bearing surface engageable on the forward side of the shoulders and which when applied pushes the shoulders rearwardly.

The invention consists in the novel form, combination and arrangement of parts hereinafter described and claimed and illustrated in the accompanying drawing, in which

Figure 1 is an elevational view of a splint embodying the invention; Fig. 2 is a cross-section on line 2—2 of Fig. 1; Fig. 3 a cross-section on line 3—3 of Fig. 1 and Fig. 4 a cross-section on line 4—4 of Fig. 1.

Referring to the illustrative embodiment of the invention 1, 2 represent two plates, preferably pressed out of aluminum, one for the right shoulder and the other for the left shoulder. The bars 3, 4 are pivoted at 5, 6 respectively to the plates 1, 2 and a slot 7 is formed in each plate through which a bolt

8 extends, the bolts also being extended through apertures formed in the bars respectively and having the wing nuts 9 thereon by which to clamp the bars to the plates in any rotated position of the plates on their pivots. The bars 3, 4 are longitudinally slotted and overlap and the bolts 10, having the wing nuts 11 thereon, are extended through the slots. By longitudinally adjusting the bars on each other the distance between the plates may be adjusted to accommodate the splint to various breadths of shoulders of patients. Since the plates are also capable of limited rotation on their pivots they may be adjusted to fit the particular contour of the forward sides of the patient's shoulders. The bars are offset relatively to the plates so that they will not bear against the chest of the patient.

Suitable pads 12 are secured to the back of the plates, and to the lower part of the plates are secured the buckles 13 which lie adjacent the slots 14 formed in the plates and the pads. The straps 15, 16 are adapted to be engaged by the buckles and extend through the slots 14, and they are also adapted to extend around the opposite sides and onto the back of the patient where they are connected by the buckle 17. These straps being connected together and to the plates 1, 2 by the buckles 17, 13 are therefore adjustable so that the proper draught may be applied to the lower part of the plates to firmly engage them on the shoulders or push them rearwardly as desired.

The straps 18, 19 are attached to the straps 15, 16 respectively and they are adapted to be engaged by the buckles 18' that are secured to the top portion of the plates respectively. The straps 18, 19 cross each other on the patient's back and when tightened draw the upper portion of the plates firmly against the shoulders. The continued tightening of all the straps causes the plates to push the shoulders rearwardly the desired amount—the injured shoulder especially in order to align the fractured segments of the clavicle.

Each plate 1, 2 is of peculiar form. In general outline it is somewhat elliptical, the upper portion being widest and flared laterally at its inner side. In its longitudinal axis the

upper portion 21 of each plate is convex in all directions and merges into a lateral concavity 22 that extends toward the lower end of the plate. The portion 23 of the plate, extending along its inner edge, in which the slot 7 is formed, is convex both longitudinally and transversely. The various curvatures are illustrated in the cross-section figures of the drawing.

When the splint is installed on a patient the convex and concave portions of the padded plates 1, 2 snugly fit the curvatures of the front side of the shoulders and the lower outer portions extend in front of the arms somewhat and substantially prevent forward movement of the arm associated with the injured shoulder. The lateral straps 15, 16 are below the scapulae so that they will not creep upwardly when the straps 18, 19 are tightened, and since the shoulder straps cross at the back their draught is rearward and inward on the plates.

The splint is very rapidly applied, the adjustments being readily accomplished, and there is no irritating member on the splint. The relatively large bearing surface of the plates enables them to produce a positive push on the shoulders without discomfort to the patient, and the draft members hold the plates firmly in position.

What I claim is:

1. A clavicle splint comprising two members shaped to engage on the front side of the human shoulders respectively, means to space the members transversely, lateral draft members adjustably connected directly to the lower ends of the members and to each other and adapted to be drawn about the rear of the trunk of the human body, and shoulder engaging draft members secured to the lateral draft members adjacent the connection of the latter to the splint members and adjustably connected directly to the upper ends of the members respectively, to pass over the shoulders, the several draft members cooperating to cause the members to push the shoulders rearwardly.

2. A clavicle splint comprising two rigid members shaped to engage the front side of the human shoulders respectively, an extensible member pivotally connected at its opposite ends to the rigid members, laterally projecting straps adjustably connected directly to the lower ends of the members, respectively and adapted to be adjustably connected together at the human back, and straps secured to the laterally projecting straps respectively adjacent their point of connection to the rigid members and adapted to be drawn over the shoulders and adjustably connected directly to the upper ends of the members respectively, the several straps cooperating to cause the rigid members to push the shoulders rearwardly.

3. In a clavicle splint including a substan-

tially rigid padded plate for engaging the front side of the human shoulder, said plate being substantially reniform in outline and having its upper end portion on the face confronting the shoulder concave transversely and longitudinally at its outer portion and having a convex portion at the inner side of the concave portion, said convex portion extending downwardly and outwardly to the lower outer portion of the plate, and means to secure said plate to the body with the upper concave portion pressing rearwardly against the clavicle and the lower convex portion in front of the upper arm.

4. In a clavicle splint including a substantially rigid padded plate for engaging the front side of the human shoulder, said plate being substantially reniform in outline and having its upper end portion on the face confronting the shoulder concave transversely and longitudinally at its outer portion and having a convex portion at the inner side of the concave portion, said convex portion extending downwardly and outwardly to the lower outer portion of the plate, a second similar plate for the opposite shoulder, means to secure the plates rigidly together in adjusted spaced and angular relation, and means to secure said plates to the body with the upper concave portions pressing against the clavicles and the lower convex portions in front of the upper arms.

5. A clavicle splint including a pair of substantially rigid members adapted to engage the human body in front of the shoulders and to project at their lower ends lower than the axillæ, rigid means in front of the body for securing said members in spaced and angular adjusted positions, an adjustable back strap connecting the lower ends of the plates and adapted to lie in spaced relation to the axillæ, and crossed shoulder straps each having one end connected to the back strap in spaced relation to an adjacent plate to lie behind the axillæ and having its other end connected to the top of the other plate.

6. In a clavicle splint, a pair of rigid and padded plates each shaped to conform throughout to the front part of the shoulder region of a human body and each having a vertically disposed buckle secured to its lower part, a back strap connecting said buckles and having its ends thereby secured adjustably to the respective plates, other buckles secured to the upper ends of the respective plates, a pair of shoulder straps arranged in cross relation each having one end secured to the first strap adjacent a respective plate and having its other end secured to the last mentioned buckle of the other plate, and rigid connecting means having its ends secured to the central portions of the respective plates.

7. In a clavicle splint, a pair of rigid and padded plates each shaped to conform throughout to the front part of the shoulder

region of a human body and each having a vertically disposed buckle secured to its lower part, a back strap connecting said buckles and having its ends thereby secured adjustably to the respective plates, other buckles secured to the upper ends of the respective plates, a pair of shoulder straps arranged in cross relation each having one end secured to the first strap adjacent a respective plate and having its other end secured to the last mentioned buckle of the other plate, a pair of rigid cross bars slidable longitudinally of each other, means to secure said cross bars in slidably adjusted position, an offset foot 10 on each cross bar having pivotal connections with the central portion of a respective plate, and means to secure the plates to the feet in pivotally adjusted positions.

In witness whereof I hereto subscribe my
20 name.

JOE J. ETTINGER.
